UNITED STATES PATENT OFFICE.

GEORGE T. REYNOLDS, OF PROVIDENCE, RHODE ISLAND.

GASOLENE OR OIL FILTER.

974,519.

Specification of Letters Patent. Patented Nov. 1, 1910.

Application filed May 4, 1909. Serial No. 493,930.

To all whom it may concern:

Be it known that I, GEORGE T. REYNOLDS, a citizen of the United States, residing at Providence, in the county of Providence, State of Rhode Island, have invented a certain new and useful Improvement in Gasolene or Oil Filters, of which the following is a specification, reference being had therein to the accompanying drawings.

The filter in which the invention resides is designed more particularly for use between an explosive engine and its gasolene supply-tank, for the purpose of filtering the gasolene on its way from the tank to the engine, although it is also intended to be employed for filtering oil and other fluids.

It has been contrived with especial reference to trapping water and dirt, without contact of the same with the filter-screen, so as thereby to obviate the clogging of the latter. Also, with reference to enabling it to be used in either a vertical position or a horizontal one, and to be combined with the pipe-connections in a variety of ways, according to the arrangement of such pipe-connections. Also, with reference to enabling the filter-screen to be removed or replaced conveniently and quickly.

The drawings show an embodiment of the invention, and represent different positions in which it may be used in practice.

Figure 1 thereof is a view of the said embodiment in elevation as employed in an upright position. Fig. 2 is a view of the same in vertical section, except the pet-cock. Fig. 3 is a view in horizontal section in the plane of line 3, 3, in each of Figs. 1 and 2. Fig. 4 is a view of the said embodiment in vertical section as employed in a horizontal position. Fig. 5 is a detail view in plan of one of the gauze disks of the filter-screen.

The filter comprises, essentially, the body or barrel 1, the cap 2, and the filter-screen 3.

At 4 is a pet-cock which is applied to the body or barrel.

The body or barrel 1 usually is made with provision for attachment to some part or support so as to keep the filter in the desired place, or support it. In this instance it is formed with a lug 1^a through which is made a hole 1^b for the reception of the stem of an attaching bolt, or the like.

Body or barrel 1 has a central chamber, open at the end where the cap 2 is applied, and two small openings communicating through its shell with the said chamber, one

thereof, 1^c, being located at one side, and the other, 1^d, at the end opposite the large opening for the cap. These openings 1^c, 1^d, are circular and correspond in diameter with the threaded shank of the pet-cock 4 and the threaded end of a pipe-connection leading to the filter. The walls of such openings are internally threaded for engagement with the said threaded portions. Either of the said openings may serve as the inlet for the gasolene, or other fluid to be filtered, and will have an end of the supply-pipe (not shown) screwed into the same. The pet-cock 4 will be applied to the other, by screwing its threaded shank in place.

The cap 2 is in screw-threaded connection with the open end of the body or barrel. In the illustrated construction it is externally threaded at its periphery, and screws into the said open end, which is internally-threaded. It is formed with an internal chamber forming a reservoir for filtered gasolene (or other fluid), and carries by its inner portion the filter-screen 3, the said inner portion being internally threaded for engagement with the externally-threaded body of the said screen. The outer portion of the cap is formed with an outlet 2^a, through which the filtered gasolene or other fluid flows from the said reservoir. The wall of the outlet is internally threaded to receive the externally-threaded end of a pipe-connection (not shown) leading from the filter.

The filter-screen 3 comprises a cylindrical body-portion or shell 3^a, and disks of gauze 3^b, 3^c, covering the opposite ends of the central opening of such shell. Each of the said disks is fastened to a ring or collar 3^e which fits within the corresponding end-portion of the shell. The latter is internally threaded adjacent its respective ends, and the rings or collars 3^e, 3^f, are correspondingly-threaded externally and screwed into the shell until they rest against the shoulders 3^d, 3^d. To facilitate turning the rings and disks, each ring has a cross-pin 3^g, which extends diametrically and may be taken hold of with one's fingers or a pair of pliers. The rings may readily be applied to the body-portion or shell 3^a, or either or both of them may be disconnected therefrom. The periphery of the body-portion or shell 3^a is exteriorly threaded, and screws into the inner portion of the cap. Thereby the filter-screen is attached to the cap so as to be supported there-

by. When the cap is applied to the barrel the filter-screen is placed in working position. When the cap is removed from the barrel it takes the filter-screen with it. The filter-
5 screen is readily applied to and detached from the cap. The filter-screen is supported by the cap within the body or barrel in a position intermediate the opening 1^c and the outlet 2^a, and with more or less space inter-
10 vening between the inner surface of the body or barrel and the central opening of the filter-screen.

The space within the body or barrel constitutes a receiving chamber for the gasolene
15 or other fluid.

When the filter occupies the vertical position in which it is shown in Figs. 1 and 2, the opening 1^c being used as the inlet, and the pet-cock 4 being fitted to the opening 1^d,
20 the filter-screen is entirely above the said inlet. Fluid entering by the inlet does not flow directly toward the filter-screen, but across below the same. Consequently impurities, such for instance as water and dirt,
25 have a chance to settle to the bottom of the receiving-chamber, without being carried against the filter-screen so as to choke its interstices. They may be drawn off, as usual, through the pet-cock 4.

30 When the filter occupies the horizontal position in which it is shown in Fig. 4, it may be disposed with opening 1^c at the under side, as in such figure, the said opening having the pet-cock applied thereto. In this case, opening 1^d serves as the inlet for the gasolene. The water and dirt are afforded an opportunity to settle down to the lower side of the receiving-chamber without being carried into contact with the gauze of the
35 filter-screen. When the filter is arranged horizontally as in Fig. 4, the distance between the bottom surface of the receiving-chamber of the body or barrel and the lower portion of the central opening of the filter-
40 screen is sufficient to allow a considerable accumulation of water and dirt below the bot-
45

tom of such central opening, and such accumulation may be drawn off from time to time by opening the pet-cock.

When the filter is used for gasolene, the 5 gauze-disks alone are required, usually. When used for oil or other liquids a suitable packing may be placed between the two disks.

What is claimed as the invention is:—

1. A filter of the class described comprising a hollow body open at one end and provided with a threaded hole at the opposite end and on one side of equal diameters, a cap containing a chamber adapted to screw 60 into the open end of said body and provided with an outlet opening, and a flange at its inner end, and a filter screen comprising an exteriorly threaded sleeve adapted to be removably screwed into the threaded flange of 65 said cap, removable filtering material within said ring held in place by detachable collars.

2. A filter of the class described comprising a hollow body open at one end and having a threaded hole through the opposite end 70 and one side and of equal diameters with their axes at a right angle to each other, said holes adapted to interchangeably receive a supply pipe and a pet-cock, a chambered cap adapted to screw into said body 75 and having a threaded hole at its outer end and an interiorly threaded flange at its inner end, and a removable filter screen comprising a sleeve screwed into said cap flange, and filter material within said sleeve retained in position by perforated disks and threaded collars in each end of the sleeve, said filter adapted to operate in either a vertical or a horizontal position by changing the positions of the inlet pipe and the pet- 85 cock.

In testimony whereof I affix my signature in presence of two witnesses.

GEORGE T. REYNOLDS.
